UNITED STATES PATENT OFFICE.

SEIZI TADAKUMA, OF PORTLAND, OREGON.

HORSESHOE.

1,150,554.

Specification of Letters Patent. Patented Aug. 17, 1915.

Application filed March 22, 1915. Serial No. 16,243.

To all whom it may concern:

Be it known that I, SEIZI TADAKUMA, a subject of the Emperor of Japan, residing at Portland, in the county of Multnomah and State of Oregon, have invented a new and Improved Horseshoe, of which the following is a specification.

This invention has for its object to provide an improved construction of horse shoe having a special coöperative arrangement of the toe and heel calk receiving portions adapted for detachably and adjustably holding peculiarly shaped toe and heel calk members that are more especially designed to provide for quickly and conveniently changing the calks from sharp shoes to mud shoes or semi-mud shoes and also for replacing worn out calks without necessitating the removal of the shoe from the hoof.

Another object of my invention is to provide an improved horse shoe of the general type stated having the toe and heel portions designed for interchangeably receiving the different forms of calks adapted for either every day or ordinary road surfaces uses for calks especially designed for use on icy, snowy or other slippery surfaces and in which the construction of the shoe body proper and the calks adapted for being interchangeably connected with the said shoe body is such, that the shoe can be economically made and the operation of taking off and replacing the calks is readily effected by the driver without the necessity of taking the horse to the blacksmith.

With the above, and other objects in view, and which will be further referred to, my invention consists of a horse shoe that embodies the peculiar features of construction and novel arrangement of the parts hereinafter described in detail, specifically pointed out in the appended claims and illustrated in the accompanying drawing, in which:

Figure 1 is a top perspective view of my improved horse shoe, the same being shown equipped with smooth calks for every day or ordinary uses. Fig. 2 is a similar view of the shoe shown in Fig. 1, the bottom side and the inner side of the toe end being the

more fully illustrated. Fig. 3 is a top plan view of the shoe body proper, the calks being omitted. Fig. 4 is a perspective view of the upper end of the shoe body shown in Fig. 3, illustrating more clearly the interlocking grooves and ribs hereinafter described. Fig. 5 is a perspective view looking at the inside of the smooth toe calk member, showing the corresponding dovetailed wedges and V shaped recesses that engage with the aforesaid ribs and grooves. Fig. 6 is a perspective view of the smooth calk member viewed from the inner side thereof. Fig. 7 is a detail perspective view of the aforesaid shoe body the calks of those adapted for winter use being shown in place. Fig. 8 is a perspective view of one of the pointed or toe ice calks hereinafter referred to. Fig. 9 is a perspective view of the heel ice calks. Fig. 10 is a cross section of the toe end of the shoe with one of the ice or sharp calk members applied for use.

My invention may be readily embodied in any of the well known forms of horse shoes.

In the present showing, the body of the shoe 1 has the ordinary arrangement of the nail holes 3, the outer ends of the said holes, that is,—that end of the holes that open through the under face of the shoe, being elongated to receive the elongated heads 49 of the nails 4 that secure the shoe to the hoof in the usual way. The heel ends 10—10 of the shoe, have reduced tongue like portions 5—5, provided with one or more transverse apertures 50—50 for the passage of the screw bolts 6—6 that extend therethrough and through the opposite apertures 70—70 in the opposite sides of the socket-like portions 71—71 of the heel calks 7, which, for the ordinary or mud-surface uses is made of cast iron and provided with a dependent smooth heel or tread portion 72, as is clearly shown in Fig. 1. For icy or slippery pavements or road uses the heel calks 7 are made of steel and their tread surfaces are provided with sharp prongs 95 or points 73—73, as is clearly shown in Fig. 7, by reference to which and to Fig. 9, it will be understood that the heel calks, when

applied, slide onto the tongue-like terminals of the heel ends of the shoe and are secured by the screws 6 and the nuts 60.

The toe end of the shoe is flat at the top or hoof engaging side which is smooth throughout its entire surface to snugly fit against the hoof as is the case in the ordinary form of horse shoes. The under or bottom side of the toe end of the shoe is provided with a $>$ shaped or undercut transverse groove 8, the upper tapered wall 80 of which is formed with a series of tapering or wedge-like ribs 81-81 that terminate at the lower or outwardly inclined wall 82, the lower edge of which communicates with a series of parallel dovetailed grooves 9 that extend across the toe end of the shoe, as is best shown in Fig. 3 of the drawing.

The toe calks, in my construction of horse shoe, when inclined for ordinary roadway uses is made of cast iron and comprises a body portion that includes a flat tread member or block 12 that is integral with and extends transversely across the bottom of a flat segmental portion 13 that merges with a vertical segmental flange 14 which, when the parts are assembled, extends upon and fits against the outer curved toe end of the shoe and for firmly holding the said toe calk against lateral motion and for fixedly holding it in the desired position in the shoe body proper the said flat segmental portion 13 of the calk has parallel dovetailed flanges 35 22 on its under face that slidably engage the dovetailed grooves 9 in the shoe body and to further provide for a rigid connection of the toe calk with the shoe body, the said calk includes a $>$ shaped filler portion 40 15 that fits within the $>$ shaped groove 8 of the shoe body and has wedge shaped grooves 16 for receiving the wedge-like ribs 81 on the wall 80 of the toe end of the shoe, as is clearly shown in Fig. 10.

For quickly applying the toe to the shoe or for removing the same as necessary, the vertical flange 14 of the calk has a pair of horizontal apertures 17-17 that register with horizontal apertures 18-18 in the toe end of the shoe, and the said apertures receive clamp bolts 20-20 which are drawn up to bring the vertical flange 14 of the calk in close contact with the front end of the shoe and for holding the rib and grooved portions of the shoe and calk in a tight engagement, by the nuts 21 applied to the inner ends of the said bolts, as is clearly shown in Fig. 2.

For icy or otherwise slippery roadways 60 "winter" calks are provided for replacing the calks 7, and the said "winter" calks, illustrated in detail are of steel, the toe calks having a series of triangular sharp creeper lugs 75 and the heel calks having

their tread faces V grooved to form sharp edges 73, as shown.

From the foregoing taken in connection with the drawings, the complete construction, the manner of use and the advantages of my invention will be readily apparent. 70

By reason of forming the toe portion of the shoe in the manner described, the change of the calks can be easily effected by the driver by simply unscrewing the bolts 6 and new calks as readily substituted. Furthermore by reason of forming the shoe with the undercut or transverse $>$ shaped recess and shaping the toe calk in the manner shown and described, the said calk is positively and firmly held against vertical or lateral 80 displacement.

What I claim is:

1. A horse shoe having a smooth uninterrupted hoof engaging top surface, one or more grooves on the under side of the toe end, said grooves extending lengthwise of the shoe, the said toe end having an undercut transverse recess that extends at right angles to the aforesaid grooves and a calk that includes a flat or base member having 90 integral pendent tread portions and upwardly projected flanges for slidably engaging the recesses in the aforesaid base member, the latter having a segmental flange for projecting over the toe end of the 95 shoe and means for detachably clamping the calk onto the said shoe.

2. A horse shoe having a smooth uninterrupted hoof engaging surface, at least one groove in its under face that extends transversely across the toe end thereof, the front face of the said toe end having a V shaped transverse recess and at least one aperture that extends transversely through the said toe end; in combination with a calk that includes a base portion having pendent tread portions, a flange on its upper face for slidably engaging the groove in the under face of the shoe, a filler portion for fitting into the V-shaped recesses of the toe end of the 110 shoe, said calk having an aperture or apertures for registering with the aperture or apertures in the toe end of the shoe and formed with a segmental flange that extends over the front end of the shoe and lock bolt 115 and nut devices that coöperate with the shoe and the calk members for detachably holding the calk members locked on the said shoe.

3. In a horse shoe, the combination with 120 the shoe body having one or more transverse grooves that extend lengthwise of the said shoe body across the under side of the toe end, and a $<$ -shaped recess across the said under side of the said toe end which extends at right angles to the said transverse groove, the tapered wall of the said $<$ -shaped recess having one or more wedge-

like ribs, of a cork that includes a base portion having transverse flanges that endwise slidably engage the transverse grooves on the under face of the toe end of the shoe, 5 the said cork also including a segmental flange that projects up over the front or toe end of the shoe and has a <-shaped filler portion for engaging the <-shaped recess in the front end of the shoe, the said filler

portion having wedge shaped grooves for 10 receiving the aforesaid wedge shaped ribs on the shoe, and means for clamping the cork member on the toe end of the shoe.

SEIZI TADAKUMA.
